(57) **CLAIM**

(21) Appl. No.: **29/356,394**

The ornamental design for a non-contact rechargeable medical thermometer, as shown and described.

(22) Filed: **Feb. 25, 2010**

DESCRIPTION

(51) **LOC (9) Cl.** **10-04**

FIG. 1 is a top plan view of a non-contact rechargeable medical thermometer;

(52) **U.S. Cl.** **D10/57**

FIG. 2 is a front elevational view thereof;

(58) **Field of Classification Search** D10/57;

FIG. 3 is a bottom view thereof;

374/1-208; 600/549

FIG. 4 is a left elevational view thereof;

See application file for complete search history.

FIG. 5 is a rear elevational view thereof;

(56) **References Cited**

FIG. 6 is a right elevational view thereof; and,

U.S. PATENT DOCUMENTS

FIG. 7 is an isometric view thereof, showing our design.
